UNITED STATES PATENT OFFICE.

ARMAND LEON FREDERIC LEFEVRE, OF ST.-DENIS, FRANCE.

AUTOMATIC GRATE FOR STEAM-BOILER AND OTHER FURNACES.

1,257,257.

Specification of Letters Patent.

Patented Feb. 19, 1918.

Application filed September 11, 1916. Serial No. 119,536.

To all whom it may concern:

Be it known that I, ARMAND LEON FREDERIC LEFEVRE, a citizen of the Republic of France, residing at 5 Rue du Jambon, St. Denis, Seine, France, have invented new and useful Improvements in Automatic Grates for Steam-Boiler and other Furnaces, of which the following is a specification.

The present invention relates to an arrangement of automatic grate, having a continuous or endless apron, for steam-boiler or other furnaces, and is designed to permit of operating either with air under pressure, (forced draft) while still leaving the front 10 end of the apron in the open air, or to operate under natural draft by opening a door provided at the front.

For the regulation of the quantity of air necessary for combustion, the invention 20 proposes a special arrangement of movable dampers and movable supporting rails therefor, the rails being operated by certain externally located connections and serving to regulate the position of the dampers.

25 In the accompanying drawing, which represents by way of example, purely indicatively and in no way limitatively, an automatic grate constructed according to the invention:

30 Figure 1 is a longitudinal section of the grate as a whole;

Fig. 2 is a transverse section along the line $x-x$ of Fig. 1, partly broken away and on a larger scale.

35 Fig. 3 is a detail on a still larger scale.

The grate consists essentially of a movable endless apron a , formed by the fire-bars proper a' , mounted in their supports a^2 connected together two by two, and with them 40 are combined the movable dampers b . The fire-bar supports a^2 are fixed at each side of the grate to the actuating chains C , which wind up, at the front and rear of the grate, on wheels c' , c^2 respectively, provided to receive them. The forward wheels c' impart the motion to the apron and with this end in view, the shaft c^3 , on which they are keyed, 45 is actuated by any suitable mechanism (not shown) in such a manner that the upper half 50 of the apron a , constituting the grate proper, moves from front to rear, that is to say from left to right in Fig. 1.

Between the wheels c' and c^2 , the apron a is supported, either by slideways (such as 55 d Fig. 2) or by antifriction rolls d' , fixed on

the sides or cheeks e of the frame of the apparatus.

The coal, introduced by any suitable means into the hopper f , falls, when the door f' is opened, on to the front of the grate a which, 60 in its movement from front to rear, takes with it a layer of coal, the thickness or height of which is determined by the position of the door f^2 . The coal is consumed gradually as it moves toward the rear with 65 the apron a and, as the latter begins to roll over the wheels c^2 , there only remains clinker on the grate, which then falls into an ash-pit provided to receive it.

The frame e of the apron a is mounted on 70 four wheels e' , running on rails e^2 of a special form. The lower portions of the cheeks of the frame e engage in grooves e^3 in said rails, so that by means of a packing the 75 passage of air can be arrested (Fig. 2).

A flexible sheet-metal plate g , fitted at the rear, and a gate h placed at the front, render it impossible for the air introduced under the grate, as shown by the arrows in Fig. 1, to take any other path than through the 80 layer of coal on the grate. Screens i and j rubbing gently against the apron a , complete the closure and prevent the passage of air anywhere except through the grate and the bed of coal thereon. When the door h is 85 closed, as shown in Fig. 1, it is possible to operate with air under pressure, introduced beneath the grate (forced draft) while leaving the apron a in the open air at the front. If the door h is opened by swinging it forward (from right to left in Fig. 1) one can 90 operate under natural draft.

The regulation of the quantity of air necessary to insure combustion is effected as follows:

The dampers b slide along two guide-rails, each of which is composed of movable sections k , k' , hinged together at k^2 . The front section k pivots by its front extremity at k^3 on the frame and the rear section k' is 100 hinged by its rear extremity at k^4 to a member k^5 which in turn pivots k^6 on the rear of the frame. The rail-sections k , k' are provided at their rear extremities with rolls k^7 upon which two cams l , l' are adapted to 105 act so as to alter the position, as regards height, of the said rail-sections. With this in view, the cams l , l' can be moved from front to rear (that is to say, from left to right in Fig. 1) and vice versa, by means of 110

operating levers m keyed on a transverse shaft m' , upon which there is also fixed, outside the frame e , a lever arm m^2 (Fig. 2) which can be acted upon by the intermediary of an actuating bar (not shown) operated from in front of the grate.

At the end k^3 of the guide-rails, the damper b always occupies the position shown at I in Fig. 1, that is, a position in which it 10 offers free passage to the air, and, if the lever m occupies its extreme position toward the left in Fig. 1, the damper would retain its position I until it arrives at the extremity k^4 of the guide-rails. It will then close 15 while traveling from k^4 to k^6 and will be completely closed (position III) at this latter point.

When the guide-rails occupy the position shown in Fig. 1, the dampers b , which are wide open from k^3 to k^2 , will begin to close immediately after having passed the point k^2 ; they will then continue to close gradually (as will be seen, for example, from position II) and will be completely closed (position III) on reaching point k^4 .

If the lever m were pushed to its extreme right-hand position in Fig. 1, the dampers b , wide open at point k^3 , would close gradually from k^3 to k^2 and would then remain closed while traveling from k^2 to k^6 .

I claim:

1. An automatic grate for steam-boiler or other furnaces, comprising an endless movable apron, firebars carried by said apron, 35 dampers associated with said firebars and movable in the direction of their height to regulate the quantity of air passing through the grate, guide means upon which the dampers along the upper run of the grate rest 40 during the movement of the grate, said guide means being movable in the same said direction as the dampers resting thereon for the purpose of regulating the positions of said dampers, and means arranged under 45 said guide means for regulating the elevation thereof, said last named means being movable in a plane at an angle to the plane of movement of the guide means and, in its movement and according to the degree and 50 direction thereof, varying the elevation of said guide means.

2. An automatic grate for steam-boiler or

other furnaces comprising a frame, an endless apron movable in said frame, firebars carried by said apron, dampers associated with said firebars and movable in the direction of their height to regulate the quantity of air passing through the grate, a guide rail upon which the dampers along the upper run of the grate rest during the movement of the grate, said guide rail being in two parts hinged together and respectively movable in the same said direction as the dampers resting thereon, the front one of said parts being pivoted to the frame, a link pivoted to the rear part and to the frame, and a means for adjusting the elevation of the parts of the guide rail relative to the firebars, thereby to effect adjustment of the positions of the dampers resting and moving on said guide rail.

3. An automatic grate for steam-boiler and other furnaces comprising a frame, an endless apron movable in said frame, fire-bars carried by said apron, dampers associated with said firebars and movable in the direction of their height to regulate the quantity of air passing through the grate, a guide rail upon which the dampers along the upper run of the grate rest during movements of the grate, said guide rail being in two parts hinged together and movable in the same said direction as the dampers resting thereon, the front one of said parts being pivoted to the frame, a link pivoted to the rear part and to the frame, a projection carried by each part of said guide rail, and a rod located between the runs of the grate and movable in a plane at an angle to the plane of movement of the guide rail, said rod having cam faces formed thereon to co-operate with said projections during the movement of said rod in adjusting the elevation of the parts of the guide rail relative to the firebars and thereby adjusting the positions of the dampers resting and moving on said guide rail.

In witness whereof I have hereunto set
my hand this 24th day of August, 1916.

ARMAND LEON FREDERIC LEFEVRE.
